W. M. GRIFFIN

MUSICAL INSTRUMENT

Filed July 31, 1926

INVENTOR.
Wayne M. Griffin,
BY *J. H. McCrae.*
his ATTORNEY.

UNITED STATES PATENT OFFICE.

WAYNE M. GRIFFIN, OF MANCHESTER, NEW HAMPSHIRE.

MUSICAL INSTRUMENT.

Application filed July 31, 1926. Serial No. 126,113.

This invention relates to musical instruments of the type designed to be held in or against the mouth and to be operated by blowing.

- 5 It is the chief object of the invention to devise an instrument of this type with which unusual musical results can be produced, and which at the same time can be manufactured economically.
- 10 The nature of the invention will be readily understood from the following description when read in connection with the accompanying drawings, and the novel features will be particularly pointed out in the 15 appended claims.

In the drawings,

Figure 1 is a perspective view of an instrument constructed in accordance with this invention;

20 Fig. 2 is a vertical, central, cross-sectional view of the device shown in Fig. 1 illustrating the device on a somewhat larger scale;

Fig. 3 is a front elevation of the device shown in Figs. 1 and 2;

25 Fig. 4 is a perspective view showing a modified embodiment of the invention;

Fig. 5 is a cross-sectional view of a part of the device shown in Fig. 4; and

30 Fig. 6 is a perspective view showing another embodiment of the invention.

Referring first to Figs. 1, 2 and 3, the construction there shown comprises a thin leaf-like reed 2 mounted in a holder which comprises a reed protector 3 and a bearing piece 4. The reed, as shown, is of approximately semi-circular shape, and it preferably is made of some very thin resilient sheet material, such as thin celluloid, fairly stiff bond paper, or the like. A thin sheet of 35 white birch bark makes a good reed, although for most purposes it is preferable to use celluloid of from say, about three-thousandths to seven-thousandths of an inch in thickness. The reed protector 3 should be 40 made of some resilient material, rubber of about the resiliency used in rubber bands or automobile tires being preferred. This protector has an aperture therethrough, the walls 5 of which preferably are bevelled, and 45 when the device is at rest the curved edge of the reed bears against the bevelled wall 5 and closes the aperture.

The bearing piece 4 may be made of either relatively inelastic material or it may be made of the same material as the protector 55 3. In fact, the parts 3 and 4 can be made integral, but the part 4 is of such proportions that it is relatively rigid. As shown in Figs. 1, 2 and 3, the parts 3 and 4 are secured together by two rivets 6—6. It should be 60 noted that the greater part of the aperture in the reed protector lies above the upper edge of the bearing piece 4, and that the surfaces of this part adjacent to the reed are rounded smoothly, as indicated at 7 in Fig. 65 2. Preferably this part 4 has a shallow smoothly curved notch 8, Fig. 3, formed in the central portion thereof and approximately opposite the middle of the aperture in the protector 3.

70 Secured to the parts 3 and 4 by the rivets 6—6 is a metal plate 9 which projects down somewhat below the lower edges of the members 3 and 4, and this part is provided with offset ears or lugs 10—10 which are positioned at opposite sides of the aperture in the protector 3.

75 In using the device the plate 9 is inserted in the mouth with the lower edge of the plate outside the lower teeth and the lower 80 lip bearing against the lower outer surface of the part 4. The upper teeth rest between the lugs 10—10 and the rearward surface of the reed protector 3 with the upper lip bearing against the rear surface of the reed protector 3. By blowing properly through the instrument the reed is vibrated, thus producing musical notes. The tones can be 85 changed partly by varying the velocity of the air and the shaping of the mouth, and partly, 90 also, by pressing with the upper lip against the upper part of the reed protector 3 and thus bending the reed more or less over the upper rounded surfaces 7 of the bearing piece 4. It will be observed that since the 95 base of the reed is anchored between the bearing piece 4 and the reed protector 3, the bending of this reed forward or toward the right, Fig. 2, over the bearing piece will have the effect of shortening the reed and thus 100 changing its tone.

The mouth and tongue should be shaped somewhat as in saying "caw" or "kor", with the upper lip pressing against the curved

portion of the reed protector around the aperture and directing the blast of air through the aperture, no air being allowed to escape around the outside of the reed protector. While blowing, the reed protector should be pressed forward slightly to ensure a good contact between this member and the edge of the reed. The tones may be controlled by shaping them in the mouth while blowing, exactly as they are shaped in whistling, but at the same time pressing against the reed protector to shorten the reed for higher tones and relieving the pressure more or less to allow the reed to lengthen for lower tones. The tone resembles somewhat that of an oboe and can be produced in sufficient volume to carry a part in an orchestra, or with sufficient softness to accompany one or two other instruments. Trills, yodles, and unique effects can also be made. Three or four notes can be produced without consciously changing the tension on the reed or its length. The reeds also can be changed whenever desired simply by taking one out and inserting a new one, the reeds being held in place by friction. Obviously also the device can be played by singing into it as in playing a zobo, gazoo, or the like.

It is not necessary to use the plate 9 and lugs 10, but the instrument can be held against the mouth with one hand.

In order to direct and amplify the tones, the instrument may be combined with a horn 12, as shown in Figs. 4 and 5. In such a construction it is preferable to mount the parts 3 and 4 in a metal clip 13 which is supported on a pivot pin 14 so that the instrument can swing toward and from its operative position to facilitate changing the reeds. The pivot pin 14 may be supported in ears 15—15 formed in the metal plate 16 which is riveted in the mouth piece of the horn, one end of this plate being turned upwardly, as shown at 17, Fig. 5, to form a stop for the instrument, limiting its swinging movement in one direction. When the device is in use the reed protector lies at approximately right angles to the axis of the horn.

Instead of mounting the protector 3 in the manner above described, it can be supported in a metal socket member 18 as shown in Fig. 6. The outer part of this member is shaped as shown at 19 to provide a bearing surface for the reed 2 approximately like the bearing surface 7 of the part 4.

While I have herein shown and described the best embodiment of my invention that I have so far devised, it will be understood that the invention is susceptible of embodiment in other forms without departing from the spirit or scope thereof.

Having thus described my invention, what I desire to claim as new is:

1. A musical instrument of the character

described comprising a leaf-like reed, and a holder for said reed including a reed protector and a bearing piece, the base of said reed being secured between said protector and said bearing piece leaving the upper 70 part of the reed free to vibrate, said reed protector being made of resilient material and having an aperture therethrough which normally is substantially closed by the reed, said protector having a surface opposite to 75 the reed, suitably constructed to be pressed against the lip of the user in playing the instrument.

2. A musical instrument of the character described comprising a leaf-like reed, and a holder for said reed including a reed protector and a bearing piece, the base of said reed being secured between said protector and said bearing piece leaving the upper 80 part of the reed free to vibrate, said reed 85 protector having an aperture therethrough for the passage of a blast of air serving to vibrate the reed and being made of resilient material whereby it may be bent to cause said reed to bend more or less over said bearing piece, and said bearing piece having a curved surface adjacent to said reed to engage the base of said reed, whereby the vibrating portion of said reed will be shortened as it is bent over said bearing piece. 90

3. A musical instrument of the character described comprising a relatively rigid bearing member, a reed protector secured to said bearing member and projecting upwardly above the same, and a reed having its base 100 portion secured between said protector and said bearing member, said protector being made of resilient material and having an aperture therethrough provided with bevelled walls against which the free edge of 105 said reed normally bears.

4. A musical instrument of the character described comprising a relatively rigid bearing member, a reed protector secured to said bearing member and projecting upwardly 110 above the same, the surfaces of said bearing member adjacent to said protector being rounded, said protector having an aperture therethrough the greater portion of which is positioned above said bearing member, and a leaf-like reed having its base portion secured between said protector and said bearing member with its free edge normally bearing against said reed protector, said reed 115 protector being made of resilient material and having a surface opposite to said bearing member suitably constructed to be pressed against the upper lip of the user in playing the instrument.

5. A musical instrument of the character 120 described, comprising a reed and a holder in which the base of said reed is mounted, said holder including a reed protector made of resilient material and having an aperture therethrough, and a bearing member, 125

said reed being secured between the protector and the bearing member and having a vibrating portion which normally substantially closes said aperture.

6. In a musical instrument of the character described, comprising a reed protector and a bearing member secured to said reed protector, and a reed secured between said member and said protector, said protector

being made of resilient material and having 10 an aperture therethrough which is normally substantially closed by the vibrating portion of said reed, a holder for said protector and said bearing member, and means on said holder suitably constructed and capable of 15 attachment to an amplifier.

WAYNE M. GRIFFIN.
